BRAIDING CARRIER

Henry Janssen, Wyomissing, Pa., assignor to
 Textile Machine Works, Wyomissing, Pa., a
 corporation of Pennsylvania

Application September 12, 1934, Serial No. 743,683

21 Claims. (Cl. 96—13)

My invention relates to carriers for textile machines and particularly to bobbin structures for controlling the tension of strands and the operation of braiding machines.

In machines for certain braiding work, as in braiding wire on underground cables, the weights of the parts and the forces involved are relatively great and, since the carriers are arranged in a circle about the braiding point and have the strong metal wires under considerable tension laterally to the bobbin-supporting standards, there is a natural tilting tendency of the standards. This tendency, when a bobbin standard is high compared to the area of the foot, causes binding of the foot plates, upwardly and downwardly at opposite sides, respectively, of the race plate, and of the heart piece radially-inwardly against the plate, resulting in undue wear of the parts and inefficient operation.

The required strand tension in such machines being relatively great, it has been considered necessary in the past to employ tension weights, which however, since they require certain perpendicular movement render the carriers of such height as to unduly subject the carrier and the machine to the adverse effects resulting from the above-mentioned tilting tendency.

It accordingly, is among the objects of the invention to reduce the tilting tendency of a carrier of the indicated character for application such as that above mentioned, by reducing the height of the standard, this result being attained by the elimination of the tension weight and its appurtenant parts, and by certain positive features of construction as will herein appear; the employment of a spring in association with a carrier for wire-braiding work, and particularly in view of the aim to maintain the carrier of reduced height, involving certain novel features of bobbin construction, as for actuating a stop-motion lever and rendering the bobbin readily renewable.

Another object of the invention is to provide a carrier structure which, by changing it, if necessary, as to strength, size or other features not departing from its basic features, shall be adapted to control the tension of a metal wire, a fine silk thread or any other braidable strand in a more uniform manner, that is, in which, when the tension is above that degree of slack which will stop the machine but which may vary over a wide range, the action of the spring on the constantly feeding strand, which must be alternately connected to and released from the spring, shall be substantially as smooth as though the spring were connected to the strand at all times.

Another object is to avoid adverse effects on the fabric from jerks of individual threads or strands which may break or relax the tension sufficiently to operate the stop-motion lever, this result being obtained by providing a member to absorb shocks to which the tension element is ordinarily subjected, and preferably by having such shock absorber also to assume the direct impact with the stop-motion lever instead of having these impacts communicated directly to the tension element as heretofore.

A further object of the invention is to provide a device of the above indicated character of simple and durable construction, economical manufacture and effective operation.

With these and other objects in view, which will become apparent from the following detailed description of the illustrative embodiments of the invention shown in the accompanying drawings, my invention resides in the novel elements, features of construction, and arrangement of parts in cooperative relationship, as hereinafter more particularly pointed out in the claims.

In the drawings:—

Fig. 1 is a top plan view of a bobbin carrier for a braiding machine and embodying the invention.

Fig. 2 is a view, in side elevation, of the device of Fig. 1.

Fig. 3 is a view, taken at right angles to Fig. 2, parts having been broken away.

Fig. 4 is a slightly enlarged view taken substantially along the line 4—4 of Fig. 2.

Fig. 5 is a detail view, taken substantially along the line 5—5 of Fig. 3.

Fig. 6 is a detail view, taken substantially along the line 6—6 of Fig. 4.

Fig. 7 is an enlarged view, similar to a portion of Fig. 2, of the structure thereof, parts being in section and others having been broken away.

Fig. 8 is a view similar to Fig. 7, showing parts in different positions.

Fig. 9 is a view taken substantially along the line 9—9 of Fig. 8, parts having been broken away.

Fig. 10 illustrates a modified form of the invention, in a view similar to a portion of Fig. 7.

Fig. 11 is a view, taken substantially along the line 11—11 of Fig. 10, and

Fig. 12 is a view, taken substantially along the line 12—12 of Fig. 10.

In practicing the invention, in a preferred form not intended as a limitation upon any of the various novel features or combinations thereof, a stop-motion member or lever is movably

mounted on a standard and normally positioned or biased away from stopping position. A strand-supporting bobbin is rotatably mounted on the standard, upon which is also mounted a mechanism or means including a structure that is biased, as by a spring, toward position to actuate the stop-motion lever to stop the machine. This mechanism is also operative, as by a brake or clutch, for holding and releasing relation to the bobbin for movement therewith, and relative thereto, responsive to variations in tension on the strand or yarn against the bobbin. The brake, clutch, or detent, as it may be considered, is of a novel and improved type having greater leverage, smoother gripping and releasing action and operates in accordance with other new features, such as acting as a lock to hold certain parts of the bobbin together.

Referring to Figs. 1 to 9, inclusive, the structure thereof comprises a base or support 15 including a pin 16, for engaging a drive gear, carrier-foot plates 17 having a heart piece 19 therebetween for cooperation with usual intersecting annular sinusoidal raceways of a braiding machine, a double-arm standard 22 having arms 23 and 24 and a top portion 26 for supporting a yarn-guide eyelet 27 and rendering the standard of inverted substantially U-shape on the carrier foot, and upstanding projections 29 for supporting a pin 30.

A lever 32, pivoted on the pin 30, is preferably of substantially strap-loop shape having a middle section 33, between the arms 23 and 24, of slightly less width than the distance between these arms, laterally extending ends or wings 34 constituting actuating dogs for engaging the usual stop motion lever of a braiding machine, and a narrow end 35 mounted on the pin 30 between the projections 29. A helical spring 37, Fig. 9, about the pin 30, has one end 38 biased upwardly against the lever 32 and the other end 39 biased downwardly against the top carrier-foot plate 17, thus biasing the lever clockwise, or upwardly, as viewed in Figs. 2, 7 and 8.

A boss 42 on the standard arm 24 has a small bore 43 and forked portions 44 inside the arm providing slots 45. A boss 47, on the arm 23, has a large bore 48 and outer end slots 49. An axle 50, having a large body shank section 51 for the bore 48 and extending nearly to the boss 42, and a small leading-end shank section 53 for the small bore 43 of the boss 42, also has a rounded end 54 on its small shank section to facilitate its insertion into the standard arms, and to constitute a reverse push button for removing the axle, and carries a transverse pin 56 for position in the slots 49.

As seen in Figs. 2 and 3, a latch member 58, constructed of strap metal, is bent on its flat sides to be of substantially U-shape, Fig. 3, thereby providing one arm 59 acting as a stop against the boss 47 and an arm 60 for movement between positions over and aside the adjacent end of the axle 50 about a pivot pin 62 on the standard arm 23. A helical spring 63 surrounds the pin 62 between the arms 59 and 60 and acts between the latch member and the boss to bias the latch clockwise, as viewed in Fig. 2, to a position in which the axle is held in place.

A bobbin structure 64 comprises an outer spool portion including an axial cylindrical wall 65, on which a strand 66 is wound, flanges 67 and 68, projecting radially inwardly from the wall 65, and spool and flanges 69 and 70 projecting radially outwardly from the cylinder 65. The flange

68 is journaled on a flange 72 of a bobbin core member or sleeve 73 having clutch projections 74 for position in the slots 45, between the forks of the portion 44 on the standard arm 24, to prevent turning of the sleeve 73.

Another bobbin core member or sleeve 75 has a flange 76 fitting the flange 67 for journal movement relative thereto and movement therewith, depending upon whether the bobbin and the sleeve are released or connected by a brake device, as will appear. The sleeve 75 has a portion telescoped into the sleeve 73 and held axially thereto, but permitted rotation relative thereto, as by a split ring 78. A helical spring 80 surrounds the core members 73 and 75 and is held at its opposite ends to the flanges 72 and 76, respectively. As better seen in Fig. 6, the sleeves 73 and 75 have axially overlapping stop projections or fingers 81 and 82, respectively, for limiting relative movement of the bobbin core parts, and 20 twist of the spring 80, to slightly less than one revolution.

The spool-end flange 69 has an axially outstanding brake band or ratchet annulus 84 on its outer side, thereby rendering the spool-end at 25 that side of counter-sunk or depressed character; the annulus 84 having a radially-inwardly-opening groove 85 of axial V-section providing clutching, wedging, braking or ratcheting surfaces. By moving the latch member 58, against the action 30 of the spring 63, to move the arm 60 from position opposite the adjacent end of the axle 50, and by pressing against the rounded end 54 of the axle, the bobbin assembly may be removed from the standard as a unit, in which the core parts, 35 including the sleeve 73 and 75 and parts thereon, are locked axially to the outer spool portions. By disconnecting a spring 98, a clutch or brake-shoe arm 92 may be moved about the axis of a pin 90 to move the brake shoe entirely out of the 40 groove 85, so that the outer and core bobbin parts may be separated.

As better seen in Figs. 7 and 8, the sleeve 75 has three substantially radial arms 87, 88 and 89 disposed in closely-related parallel plane relation to the adjacent end of the bobbin; the arm 87 pivotally supporting, as by a pin 90, a brake-shoe arm or lever 92 having, at one end, or on a short arm thereof, a clutch member, brake shoe or detent portion 93 of substantially 50 V-section conforming to the groove 85, and, at its other end, or on its longer arm, a hook 95 and a stop portion 96. A tension spring 98, connected between the hook 95 on the lever 92 and a similar hook 99 on the arm 88 biases the brake 55 shoe 93 toward the groove 85 for intermittent braking coaction therewith.

The structure including the sleeve 75 and the arms 87, 88 and 89 is biased counterclockwise, in the direction of an arrow A, as viewed in Fig. 60 8, by the spring 80 inside the bobbin, such that it tends to assume the position wherein the arm thereof engages a cooperating stop or lug 100 on the standard arm 23. In this position, the spring 98, by the long leverage of the arm 92, 65 engages the brake shoe 93 to the sides of the V-groove 85 to effectively grip the latter so that, when tension is exerted on the strand 66, in feeding off the bobbin, all of the bobbin parts, except the core member 73 relative to which the 70 other parts are journaled, move clockwise, in the direction of the arrow B, in Fig. 7, against the action of the spring 80. At approximately the end of a revolution, during which the spring 80 becomes fully wound, the stop 96 engages the 75

stop 100, as seen in Fig. 7; whereupon arms 89 and 92 move relative to each other against the action of the spring 98 to release the brake shoe 93 from the brake 85, to allow the spool to rotate freely on the flanges 73 and 75, and to thereby, permit more than the single turn of the strand 66, thus unwound, to feed off the bobbin. The spring 80, being thus momentarily relieved of the strand tension, tends to return the inner or brake-shoe-carrying parts to starting position free from the outer spool parts, whereupon, after a certain returning movement, the spring 98 again acts to engage the brake shoe to the brake. In this way, and by intermittent repetition of this action, the strand is continuously fed from the outer spool, which also continuously rotates, but does so by so many and so rapidly repeated connections to, and disconnections from, the bobbin core and spring parts, as to obtain nearly the effect of having the strand continuously spring tensioned. This is, in a fine degree, different from a pawl and ratchet device, as in the modified form of the invention shown in Figs. 10, 11 and 12, in that in the latter, the strand is released from and reengaged to the spring in uniform steps, each form having its uses and applications, but the wedge-brake form above described operating instantaneously at any part in the bobbin movement irrespective of ratchet steps.

When the strand breaks, or relaxes its tension to sufficient degree, the parts are returned to the position of Fig. 8 wherein the arm 89 not only engages the stop 100 but also moves the lever 32 downwardly, against the action of its spring 37, to cause one of the wings 34 to actuate the stop-motion lever.

It will readily be appreciated that the members 85 and 93 effect and operate as a clutch mechanism for intermittently connecting and disconnecting the tensioning spring 80 to and from the bobbin, inasmuch as this action may take place at any instant and does not require that the associated elements be moved to predetermined positions in order to effect proper operation thereof. The clutch elements 85 and 93 function to anchor the bobbin to the tensioning spring 80 during rotation of the bobbin from the position shown in Fig. 8 until the stop portion 96 abuts the stop 100, whereupon the clutch member 93 is disengaged from the annular clutching surface 85 and free unwinding rotation of the bobbin is permitted. Immediately subsequent to the disengaging of the clutch member 93 from the annular flange 85, the action of the spring 80 rotates the sleeve 75 in the direction of the arrow shown in Fig. 8, thus the member 96 is moved clear of the stop 100, whereupon the clutch element 93 is moved into clutching engagement with the annular clutching surface 85 through the action of the spring 98. Thus the entire device serves as a tensioning structure for the yarn fed therefrom, and includes elements which successively operate: as a brake to reduce the rotative speed of the bobbin; as a clutch to engage the core structure to the bobbin; and as a detent to anchor the core structure to the bobbin to prevent relative movement therebetween.

In the modification of the invention shown in Figs. 10, 11 and 12, aside from minor differences of size and form, the parts are similar to those above described, except that, in the place of the brake annulus having the V-groove 85, there is provided a ratchet wheel 102 having internal

teeth, and, in the places of the brake-shoe arm 92 and its shoe 93, there are the pawl 103 and its detent 104. An end 106 of the sleeve 75, corresponding to the arm 87, has guide edges 107 on which channeled sides 108 of the pawl 103 slide in a slot between the edges 107; the pawl also having a portion 109 for engagement, at the end of its clockwise movement, with a stop 110, similar to the stop 100. A portion 112 on the sleeve end 106, like the arm 89, is for engagement, at the end of its counterclockwise movement, with the stop motion lever 32 and the stop 110. A spring 114, between the pawl 103 and the sleeve end 106, corresponds to the spring 98. The ratchet wheel 102 is secured to the bobbin cylinder, as by screws 116, and has a flange 117 corresponding to the flange 69. Further, the axle extends through the bobbin in the opposite direction, as indicated by the position of the small shank portion 53 and the rounded end 54 adjacent to the ratchet.

This device operates similarly to the form first described, except that the bobbin is released by, and moves relative to the brake or ratchet in uniform steps.

Of course the improvements specifically shown and described, by which I obtain the above results, can be changed and modified in various ways without departing from the scope of the invention herein disclosed and hereinafter claimed.

I claim:

1. A carrier for a braiding machine and the like, comprising a standard, and a structure mounted on the standard including a spool portion for rotatably holding a coiled strand, and a spring for operation between the standard and said spool portion to bias the latter in strand-winding direction thereon toward an initial position.

2. A carrier for a braiding machine and the like, comprising a standard, and a composite bobbin structure including a holding portion engageable with the standard to prevent rotation thereon, a portion rotatable relative to said holding portion, a spring connected between said holding and said rotatable portions, a spool portion supported by and movable relative to said holding and rotatable portions, and means intermediate said spool and rotatable portions for controlling relative movement therebetween.

3. A carrier for a braiding machine and the like, comprising a standard, and a structure mounted on the standard including a spool portion for rotatably holding a coiled strand, a spring for operation between the standard and said spool portion to bias the latter in strand-winding direction thereon toward an initial position, and a portion constituting a complete enclosure for said spring.

4. A carrier for a braiding machine and the like comprising a standard, a bobbin structure including a spool portion rotatably mounted on the standard, and a spring encased by said bobbin structure and connected between the standard and said spool portion for biasing the latter in strand-winding direction thereon toward an initial position.

5. A carrier for braiding machines and the like, comprising a bobbin having relatively rotatable core and spool portions, and cooperating complementary interfitting brake elements on the core and spool portions, respectively, and operating to control movement of said spool portion relative to said core portion.

6. A carrier for braiding machines and the like, comprising an upright frame including horizontal side bosses, a bobbin core structure comprising longitudinal sections rotatably supported between said bosses and having axially-spaced flanges, a bobbin journaled on said flanges, and a yielding connection between said bobbin and said core structure.
7. A carrier for braiding machines and the like comprising a bobbin having relatively rotatable core and spool portions, and means including cooperating brake elements on the core and spool portions respectively for simultaneously controlling the rotative and axial positioning of said spool portion relative to the core portion through the coaction of said elements.
8. A carrier for a braiding machine and the like, comprising a standard, a bobbin rotatably mounted on the standard and carrying a braking annulus of substantially wedge-section, a cooperating rotatable brake-shoe element having a complementary section for wedge-braking coaction with said braking annulus, and means associated with said brake-shoe element for biasing said bobbin in thread-rewinding direction.
9. A carrier for a braiding machine and the like, comprising a standard, a bobbin rotatably mounted on the standard and carrying a braking annulus of radially-inwardly extending substantially V-section, a cooperating rotatable brake-shoe element having a complementary section for radially-outward wedge-braking coaction with said braking annulus, and means associated with said brake-shoe element for biasing said bobbin in thread-rewinding direction.
10. A carrier for a braiding machine and the like, comprising a standard, and a composite bobbin structure detachably mounted as a unit on the standard including a holding portion engageable with the standard to prevent rotation thereon, a portion rotatable relative to said holding portion, a spring connected between said holding and said rotatable portions, a spool portion supported by and movable relative to said holding and rotatable portions, and means intermediate said spool and rotatable portions for controlling relative movement therebetween.
11. A carrier for a braiding machine and the like comprising a bobbin carrying an annular braking element, a brake-shoe support mounted for movement about the axis of the bobbin, and a lever pivoted to said support radially from said axis adjacent to said element having a sort arm constituting a brake shoe for said element and a long arm for actuating the brake shoe.
12. A carrier for a braiding machine and the like comprising a standard having a stop portion, a bobbin structure including members mounted on the standard for rotative movement relative thereto and to each other, one of said members carrying an annular braking element, a brake-shoe element movably mounted on the other of said rotatable bobbin members and having a portion for engagement with said stop portion to release the brake, and a spring operating between said other bobbin member and said brake-shoe element biasing the shoe toward braking position.
13. A carrier for a braiding machine and the like comprising a standard including oppositely-disposed uprights having aligned transverse hollow bosses, one of which has a shoulder, a bobbin comprising a hollow core including sections having coacting portions limiting relative rotation thereof, said sections having spool-bearing por-
- tions, a helical spring surrounding the core and connected between said sections, said sections telescoping each other and having adjacent ends, a member between said ends holding the sections longitudinally, an element on one of said flanges cooperating with said shoulder to prevent rotation of the corresponding core section, a spool portion of the bobbin journaled on said bearing portions, and a spindle extending through said core and said bosses.
14. A carrier for a braiding machine and the like, comprising a standard, a stop-motion operating lever movably mounted on the standard and normally disposed away from stopping position, a strand supporting bobbin rotatably mounted on the standard including an angular flange having an internal clutching surface, and means mounted on the standard including a structure biased toward position to actuate said operating lever to stop the machine and operative for holding and releasing relation to the bobbin for movement therewith and relative thereto to engage said clutching surface responsive to variations in tension on the strand against the bobbin tension.
15. A carrier for a braiding machine and the like, comprising a standard, a stop-motion operating lever movably mounted on the standard and normally disposed in inoperative position, a bobbin rotatably mounted on the standard, a member movably mounted on the standard and biased to actuate said lever to stop the machine, and an element movably mounted on said member for moving said member with, and relative to, the bobbin, responsive to variations in tension on the strand against the bobbin tension.
16. A carrier for a braiding machine and the like, comprising a standard, a stop-motion operating lever movably mounted on the standard and normally disposed away from operative position, a bobbin rotatably mounted on the standard, a member movably mounted on the standard and biased to actuate said lever to stop the machine, and means for holding and releasing said member relative to the bobbin responsive to tension variations of the strand against the bobbin tension comprising an element movably mounted on said member, means biasing said element toward the bobbin, and means for moving said element away from the bobbin.
17. A carrier for a braiding machine and the like, comprising a standard, a bobbin rotatably mounted on the standard carrying an annular brake element, a brake-shoe support mounted for movement on the standard coaxially with and relative to the bobbin, a spring biasing said support in the rewinding direction of the bobbin, a brake-shoe lever pivotally mounted on said support radially from the axis thereof, a spring between the brake-shoe lever and support biasing the shoe toward braking position, and a member for moving the brake-shoe lever relative to its support against its bias to release the brake.
18. A carrier for a braiding machine and the like, comprising a standard, a member movably mounted on the standard for stopping the machine and normally disposed away from stopping position, a bobbin rotatably mounted on the standard carrying an annular series of ratchet teeth, a pawl support mounted for movement on the standard co-axially with and relative to the bobbin, a spring biasing said support in the rewinding direction of the bobbin toward position engaging said stop member, a pawl reciprocably mounted on said support for engaging said teeth.

to move with the bobbin and to move the bobbin in rewinding direction, a spring between the pawl and its support biasing the pawl to ratchet-engaging position, and means for moving the pawl relative to its support against its spring to release the ratchet and the bobbin.

19. A carrier for a braiding machine and the like comprising a standard, a member movably mounted on the standard for stopping the machine and biased away from stopping position, a bobbin rotatably mounted on the standard carrying a portion having annularly disposed holding portions, an arm pivotally mounted on the standard about the axis of the bobbin, a lug on the standard, a spring connected between the standard and said arm biasing the arm to position against said machine-stopping member to stop the machine, an element movably mounted on said arm for holding relation to said annularly disposed holding portions, and a spring between the arm and the element biasing the element to said holding relation, said element being positioned for engagement with said lug to release the element from the bobbin.

20. A carrier for a braiding-machine and the like, comprising a standard having a bobbin-bearing portion, a support portion and a lug, a stop-motion member normally mounted on said support portion and normally disposed in inoperative position, a bobbin core structure comprising longitudinal sections having limited relative movement about the core axis, one of said core sections being held by the standard against turning, a spring connected between said core sec-

tions, means detachably mounting said core structure on said bearing portion, a bobbin journaled on said core structure and having annularly arranged braking portions, a brake support fixed to the movable core section for engagement with said stop-motion member, and a brake shoe mounted on said brake support biased for braking cooperation with said bobbin braking portions and positioned for engagement with said lug to release the brake.

21. A carrier for a braiding-machine and the like, comprising an upright frame including horizontal side bosses, a pivot support on the frame carrier foot, a stop-motion member pivoted on said support, a spring biasing said member upwardly, a bobbin core structure comprising longitudinal sections relatively movable about the core axis but engageable to limit such movement and having axially-spaced flanges, one of said core sections being operatively held by one of said bosses, a helical spring surrounding said core section connected between said sections, a spindle removably disposed longitudinally through said core sections and mounted in said bosses, a bobbin journaled on said flanges and having an annular radially-inwardly opening side braking groove of V-section, an arm fixed to the movable core portion for engagement with said stop-motion member, a lug on the frame, a brake-shoe lever pivoted on said arm in position to engage said lug and having a portion conforming to said groove, and a spring between the arm and the lever biasing the shoe toward braking position.

HENRY JANSSEN.
